(57) **CLAIM**

The ornamental design for a sandwich press, as shown and described.

DESCRIPTION

FIG. 1 is an upper, front, left perspective view of a sandwich press;

FIG. 2 is a lower, rear, right perspective thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Features shown above the dot-dash boundary line visible in FIGS. 1-6, i.e., the portion of the handle above the connection to the press body and a part of the press body that forms the food opening, form the claimed invention. Features shown in dashed line form no part of the claimed design.

1 Claim, 7 Drawing Sheets
